UNITED STATES PATENT OFFICE.

WILLIAM H. GEORGE, OF FAIRFIELD, IOWA, ASSIGNOR TO THE DEXTER COMPANY,
OF FAIRFIELD, IOWA, A CORPORATION OF IOWA.

DRAIN SPOUT FOR WASHING MACHINES AND THE LIKE.

Application filed June 1, 1922. Serial No. 565,058.

To all whom it may concern:

Be it known that I, WILLIAM H. GEORGE, a citizen of the United States, and a resident of Fairfield, in the county of Jefferson 5 and State of Iowa, have invented certain new and useful Improvements in Drain Spouts for Washing Machines and the like; and I do hereby declare that the following is a full, clear, and exact description thereof, reference being had to the accompanying drawings, and to the letters of reference marked thereon, which form a part of this specification.

This invention relates to improvements in 15 drain spouts for washing machines and the like and consists of the matters herein-after described and more particularly pointed out in the appended claims.

The primary object of the invention, is 20 to provide in a domestic washing machine of the cabinet type, a simple and efficient means by which the wash water may be drained from the machine, without spilling or splashing.

25 A further object of the invention is to provide in the casing, a small, spring pressed door, which when closed, in no manner projects beyond the casing nor mars the appearance thereof, and which 30 when opened, forms a spout which catches the water as it issues from the water container within the casing and directs it into a bucket placed in position without the casing.

35 Still a further object of the invention is to so construct the door, that it is securely held in its full open or closed position so that it in no way interferes with the operation of the washing machine, or the movements of the person using the same.

40 These objects of the invention as well as the many advantages thereof, will more fully appear as I proceed with my specification.

45 In the drawings:—

Fig. 1 is a perspective view of a domestic washing machine of the cabinet type, wherein the spout supporting door forming 50 a part of my invention, is shown in its closed position.

Fig. 2 is a view in front elevation of a fragment of the washing machine casing, showing the spout supporting door in its open position, with the scoop shaped spout

in position to direct the water from the 55 drain or faucet into an ordinary bucket.

Fig. 3 is a vertical sectional view on an enlarged scale, as taken on the line 3—3 of Fig. 1 and shows the door or flap in its closed position.

Fig. 4 is a view in elevation of the parts shown in Fig. 3.

Fig. 5 is a view similar to Fig. 3 with the door or flap in its open position.

Fig. 6 is a horizontal detail sectional view 65 as taken on the line 6—6 of Fig. 4.

Fig. 7 is a perspective view of the door or flap plate when removed from the casing.

The invention is herein illustrated as applied to the casing or cabinet of a domestic 70 washing machine, wherein there is provided in one wall of the cabinet, an opening through which the faucet on the wash water container may be conveniently reached for manipulation when it is desired to empty or 75 drain the same. In connection with this opening I provide a door which in one position closes said opening and which, in a second position acts through a coacting spout to discharge the wash water issuing 80 from the faucet into a bucket placed outside the casing.

Referring now in detail to that embodiment of the invention illustrated in the accompanying drawings, 10 indicates as a whole, the casing of a washing machine of the cabinet type, and 11 (see Fig. 3) indicates the wash water container 85 thereof, which is provided at its lowest point with a drain cock or faucet, 11^a. Said casing is made of sheet metal and includes an upright end wall 12 having a rectangular opening 13 therein, the top of which is arranged in a plane substantially coincident with the bottom of the container. The opening 13 is defined at its top and sides by an inturned flange 14 which acts to stiffen the casing wall in the vicinity of 90 said opening.

15 indicates a rectangular plate (see Fig. 7) of a width slightly greater than that of the opening 13. Said plate has a transverse bend or shoulder 16 between its ends, so that the shorter end 17 is offset into a plane 100 different from that of its longer end 18. At the ends of the shoulder 16, said plate is cut away to provide two notches 19, so that the shoulder 16 may engage and rock or swing 105

upon the bottom edge of the opening as a fulcrum, the notches 19 engaging the opposite sides of the casing wall in a manner preventing displacement of the plate relative to the opening. One marginal part of the shorter end of said plate is cut longitudinally and curled over to provide a lug or projection 20 for a purpose to appear later.

Fixed to the plate 15 is a spout 21. This 10 spout is scoop shaped and includes a bottom wall 22 which is riveted to the plate, and angularly disposed side and end flanges 23, the side flanges tapering in height toward and terminating at the edge of the 15 longer end of said plate.

On the inner surface of the casing wall, adjacent one of the side flanges 14, is secured a leaf spring 24 which is bent near its free end to provide a notch 25, said 20 spring coacting with the stop lug 20 of the plate 15 to hold said plate in the desired position.

When the parts are in their normal position, as shown in Figs. 1 and 3, the longer 25 end 18 of the plate 15 closes the opening 13 from the outside of the casing, the free end of the spring 24 so engaging the stop lug 20 as to hold the plate in this position. It will be noticed from Fig. 3 that the spout 30 21 in no manner interferes with the oscillation of the container 11, which in this particular case, is one which is adapted to hold both the wash water and the clothing to be washed, said container being oscillated by 35 suitable mechanism enclosed within the casing.

When the clothes washing operation has been completed and it is desired to drain the container 11, the plate 15 is swung about 40 its shoulder 16 as a fulcrum, into the open position shown in Fig. 5. To facilitate the opening swinging movement of the plate, it is provided at its outer end with a notch into which the thumb nail may be inserted.

When the plate is in its open position 45 it is inclined downwardly and outwardly from the inside of the casing, the lateral margins of the shorter or inner end of the plate engaging the bottom ends of the side 50 flanges 14, which are bevelled to form stop shoulders therefor. In addition to said stop shoulders, the lug 20 and notch 25 in the leaf spring 24 are so correlated and proportioned that the lug will engage in said notch, so 55 that the plate cannot swing back into its closed position under the action of the water issuing from the faucet or cook 11^a after the same is opened for the purpose of draining the container 11.

Water issuing from the faucet will strike 60 the angularly disposed rear end of the spout and will then flow down the bottom wall thereof to discharge into a bucket or other receptacle placed there for that purpose. By reason of the water falling upon the angularly disposed rear end of the spout, as it 65 issues from the faucet, there is no splashing upon the operating parts of the washing machine within the bottom end of the casing 70 10.

The simple and efficient means for holding the plate in its open position against self-closing under the action of the water discharged upon the spout, also holds said plate in its closed position so that the plate and spout cannot accidentally swing into an open position when the washing machine 75 is in operation.

The device consists of but a few parts 80 which may be made at a low cost and may be easily assembled in place, and when so assembled does not mar or detract from the appearance of the washing machine.

While in describing my invention, I have 85 referred to certain details of mechanical construction and arrangement of parts I do not wish to be limited thereto except as may be pointed out in the appended claims.

I claim as my invention.

1. In combination, a casing having a wall 90 provided with an opening, a water container within the casing, a water spigot adapted to discharge from said container and spaced back of said casing wall, a plate having a transverse shoulder formed between its 95 ends, said shoulder engaging said wall at the bottom edge of said opening, the part of the plate beyond said wall being adapted to close flat against said wall to cover said opening, an open spout carried by said plate having a receiving end adapted to be brought under said spigot with its discharge end projecting beyond said opening, and co-acting means on the casing wall and plate for yieldingly holding the plate in position 100 to close said opening or in a position with the spout under said spigot.

2. In a device of the kind described, a plate having a transverse shoulder formed between its end and notches at the ends of 110 said shoulders, one longitudinal margin of said plate at one end thereof being slit to provide a bent-over tongue, and a spout member fixed to one side of said plate.

In testimony that I claim the foregoing 115 as my invention, I affix my signature this 26 day of May, A. D. 1922.

W. H. GEORGE.
